UNITED STATES PATENT OFFICE

160,674

DISPLAY STAND

Edward W. Waltz, Grand Rapids, Mich., assignor to The E. O. Bulman Manufacturing Company, Inc., Grand Rapids, Mich., a corporation of Michigan

Application March 13, 1950, Serial No. 8,504

Term of patent 14 years

(Cl. D80—9)

To all whom it may concern:

Be it known that I, Edward W. Waltz, a citizen of the United States, residing at Grand Rapids, in the county of Kent and State of Michigan, have invented a new, original, and ornamental Design for Display Stand, of which the following is a specification, reference being had to the accompanying drawing, forming part thereof.

Fig. 1 is a side elevation of a display stand, showing my new design.

Fig. 2 is a plan view of the same and

Fig. 3 is a perspective view of the same.

I claim:

The ornamental design for a display stand, as shown.

EDWARD W. WALTZ.
